UNITED STATES PATENT OFFICE

2,041,033

CAR DOOR

Conrad R. Vegren, Chicago, Ill., assignor, by
mesne assignments, to The Youngstown Steel
Door Company, Cleveland, Ohio, a corporation
of Ohio

Application April 9, 1934, Serial No. 719,621

8 Claims. (Cl. 20—22)

This invention relates to car doors and is directed primarily to sliding doors for railway house cars.

- It is an object of this invention to provide a railway house car in which a door opening formed in a side thereof is adapted to be closed by a sliding door and in which a gutter or trough is provided at the upper portion of the opening in the closed position of the door for trapping and 10 draining off water outwardly of the door without necessitating coping of the posts disposed at the vertical portions of said opening or of the guard strip or the like secured to the posts to permit such drainage.
- 15 A further object is to provide a sliding car door, the upper horizontal margin of which is reinforced by a member presenting a gutter or trough for catching and draining water or the like outwardly of said door.
- 20 A further object is to provide a single panel door having a trough along its upper horizontal margin for collecting and draining water outwardly of said door.

A further object is to provide a sliding car door, the upper margin of which is reinforced by a member secured upon the outer face of said door and presenting a trough for the collection and drainage of water outwardly of said door.

A further object is to provide a sliding car door carrying a member presenting a trough upon the upper horizontal margin thereof, said member being incorporated in the door so as to provide an extension of the panel of the door, thereby permitting a decrease in the height of 35 the panel.

Other objects of the invention will become clear as the description thereof proceeds.

In the drawing forming a part of this specification:

- 40 Figure 1 is a fragmentary elevation of a car door applied to a side of a railway house car and embodying applicant's invention;

Figure 2 is a horizontal section taken on line 2—2 of Figure 1;

- 45 Figure 3 is a horizontal section taken on line 3—3 of Figure 1;

Figure 4 is a vertical section taken on line 4—4 of Figure 1;

- Figure 5 is a vertical section taken on line 5—5 50 of Figure 1; and

Figure 6 is a vertical section similar to Figure 4 illustrating a modification of the invention, together with its applicability to a lift door.

The invention illustrated in the drawing is 55 directed to an improvement upon the invention

disclosed in the patent to G. R. Treptow, No. 1,943,640, January 16, 1934. In this patent a substantially J shaped header is utilized to provide a trough for the purpose of collecting and carrying off water or the like which may be forced over the upper edge of the door. Disposal of the water so collected outwardly of the door is provided for by the extension of the header beyond the rear door post and for this purpose it was necessary to cope or modify the door post in 10 order to permit such extension. By applicant's improvement the labor and expense of the coping operation of the post is avoided while the desirable feature of preventing ingress of water or like into the car is retained.

Referring to the embodiment of the invention illustrated in Figures 1 to 5, inclusive, the numeral 10 designates generally a portion of the side of a railway house car provided with the customary opening 11 defined in part by means of a side 20 plate 12 and front and rear vertical door posts 13 and 14. The opening 11 is adapted to be closed by means of a car door 15 which is preferably mounted for sliding movement upon the car side 10. The car door selected for purposes of illustration comprises a metallic panel 16 which may be provided with spaced horizontal corrugations 17, merging at their ends with vertical corrugations 18 and 19 formed in the panel. A reinforcing substantially channel shaped member 20 is secured to the front margin of the metallic panel 16 and is adapted to coat with a front stop 21 in order to weatherproof said margin of the door. A reinforcing angle member 22 is secured to the rear margin of the door, this member 30 comprising a flange 23 disposed upon and secured to the outer face of the metallic panel and a transversely extending flange 24 directed toward the side of the car. A sealing strip 25 is secured upon the inner face of the metallic panel 40 16 and is adapted to coat with a guard strip 26 in order to weatherproof the rear margin of the door.

The upper horizontal margin of the door is adapted to be reinforced by means of a substantially Y shaped member 27 which presents a trough 28 and a depending securing flange 29. The reinforcing member 27 may be formed of a rolled section which is originally T shaped and embodies, in addition to the attaching or head 50 flange 29, the head flange 30 and stem 31. As clearly shown in Figure 4 of the drawing the head flange 29 is offset relative to the head flange 30 in order to permit the latter to lie in the plane of the panel so as to constitute an extension 55

thereof. The stem 31 is deformed as illustrated in this figure so that, in conjunction with the head flange 30, a trough 28 is provided. The trough 28 is provided for the purpose of collecting water or the like before it is forced across the top of the door and into the car. To provide for drainage of the water so collected the ends 32 and 33 of said trough are left open whereby any such collected water will be disposed of outwardly of the door. While this construction of the trough to permit disposal of the water is preferred, it will be apparent that the ends of the trough may be closed if desired and drainage openings provided in the bottom thereof so as to carry off the collected water.

The door 15 is guided during its sliding movement and maintained upon the side of the car 10 by means associated with the upper margin of the door. To this end a header angle 34 may be utilized to prevent the door falling into the opening during sliding movement. The header angle is secured as by means of welding to a retaining plate 35 secured as by means of rivets 36 to the depending leg 37 of the side plate. The retaining plate is preferably in the form of a Z member, the web 38 of which is directed outwardly from the side plate and bent downwardly to provide a flange 39 disposed in overlapping relationship with the upper margin of the door. The flange 39 is bent downwardly and inwardly, as shown in Figure 5, for the extent of the door opening in order to enhance the weatherproofing construction at the upper margin of the door. Adjacent the angle stop member 21 the flange 39 extends vertically as shown at 40. To permit such extension of the flange the outwardly and rearwardly directed flange 41 of the angle stop member is coped as indicated at 42.

As clearly shown in Figures 2 and 3 of the drawing the reinforcing member 27 extends between the front and rear vertical edges of the door. To permit such extension at the front edge of the door the edge 32 of the reinforcing member 27 is coped as indicated at 43 to avoid fouling of said edge upon the outwardly and rearwardly directed flange 41 of the front stop angle member 21. However, if desired, the flange 31 of the trough 28, provided by the reinforcing member 27, may merely be bent inwardly for the same purpose. To permit extension of the reinforcing member 27 to the rear edge of the door the flange 23 of the rear reinforcing angle 22 is coped as indicated at 44. As noted hereinabove, the flange 30 of the reinforcing member 27 is disposed in the plane of the panel 16. In order to reinforce or back up this flange 30 the sealing strip 25 is extended upwardly so as to abut said flange. This is clearly indicated in Figure 4 of the drawing.

In Figure 6 of the drawing there is illustrated a modification of applicant's invention, together with a showing of the adaptability of applicant's construction to a lift door as well as to the straight sliding door illustrated in Figures 1 to 5, inclusive, of the drawing. In this embodiment of the invention the reinforcing member for the upper horizontal margin of the door takes the form of a plurality of plates 45 and 46. The plate 45 is provided with an offset portion 47 so as to present a flange 48 extending above and lying substantially in the plane of the panel 16 and a flange 49 disposed upon the outer face of the panel and secured thereto as by means of rivets 50. The plate 46 comprises the angularly related flanges 51 and 52, the flange 51 being the se-

curing flange and connected to the flange 49 by means of the rivets 50. The flanges 48 and 52 of the plates 45 and 46 cooperate to provide a trough 53 which, as in the previous embodiment of the invention, is disposed so as to trap water and other foreign substances and to drain the same outwardly of the door. Where a lift door is utilized the position thereof when elevated is indicated by the dot and dash lines in Figure 6.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. In a railway house car, the combination with vertical front and rear door posts defining a door opening in a side of said car and a sliding door 20 for closing said opening, said door posts extending outwardly beyond said car side, of means presenting a trough extending across the upper part of said door opening, one end of said trough being open and projecting longitudinally beyond the rear door post, while maintaining the integrity of said post, whereby said trough is adapted to collect water and drain the same outwardly of said door when the latter is in closed position without necessitating coping of said post. 30

2. A car door comprising a sheet metal panel and a reinforcing member secured to the upper horizontal margin of said panel, said member embodying a trough, one of the sides of said trough being disposed in substantially the main plane of said panel so as to constitute an extension thereof whereby said panel may be reduced in height.

3. A car door comprising a sheet metal panel and a reinforcing member secured to the upper horizontal margin of said panel, said member embodying a trough, one of the sides of said trough being disposed in substantially the main plane of said panel so as to constitute an extension thereof, whereby said panel may be reduced in height, 45 said trough having open ends.

4. A car door comprising a panel and a reinforcing member secured to the upper horizontal margin of said panel, said member being substantially Y shaped in section and providing a trough for the collection of water and a flange depending therefrom, said flange being secured to said panel, said trough being disposed above the upper horizontal edge of said panel.

5. A car door comprising a panel and a reinforcing member secured to the upper horizontal margin of said panel, said member being substantially Y shaped in section and providing a trough for the collection of water and a flange depending therefrom, said flange being secured to said panel, said trough being disposed above the upper horizontal edge of said panel, a portion of said trough lying in the plane and forming an extension of said panel, whereby a reduction in height of said panel is effected. 65

6. In a railway house car, a sliding car door, said door comprising a panel and a horizontally extending reinforcing member secured to the upper margin of said panel, said reinforcing member embodying a trough disposed substantially outwardly of said panel, and a retaining member for said door secured to said car and having a downwardly extending flange disposed in overlapping relationship with said reinforcing member, said flange being spaced outwardly of said 75

trough, whereby said trough is adapted for the collection of water, said trough being formed to drain collected water outwardly of said door.

7. In a railway house car having vertical, front and rear door posts defining a door opening in a side of said car, said door posts projecting laterally outwardly beyond said car side, a sliding door for closing said door opening, means secured to the upper margin of said door providing a longitudinally extending trough, an end of said trough being open and projecting beyond the rear door post in laterally spaced relation thereto to maintain the integrity of said door post, said trough being adapted to collect water and drain the same outwardly of said door through said trough end when the door is in closed position without necessitating coping of said post.

8. In a railway house car having vertical,

front and rear door posts defining a door opening in a side of said car, said door posts projecting laterally outwardly beyond said car side, a sliding door for closing said door opening, a metallic member substantially equal in width to the width of said door secured to the upper margin of said door, said member embodying a trough disposed above the upper horizontal edge of said door and a depending flange secured to said door, said trough having at least one open end extending beyond said rear door post in laterally outwardly spaced relation to said post to maintain the integrity thereof, said trough being adapted to collect water and drain the same through the open end outwardly of said door when the latter is in closed position, without necessitating coping of said post.

CONRAD R. VEGREN.
